UNITED STATES PATENT OFFICE.

WALTER H. PAULSON, OF CHICAGO, ILLINOIS, ASSIGNOR TO HARRY D. LATHROP, OF CHICAGO, ILLINOIS.

CAN-WASHING MACHINE.

1,423,816.

Specification of Letters Patent. Patented July 25, 1922.

Original application filed May 22, 1920, Serial No. 383,333. Divided and this application filed May 22, 1920. Serial No. 389,334.

To all whom it may concern:

Be it known that I, WALTER H. PAULSON, a citizen of the United States, and a resident of the city of Chicago, county of Cook, and State of Illinois, have invented certain new and useful Improvements in Can-Washing Machines, of which the following is a specification.

My invention relates to improvements in can washing machines, and more particularly to means for feeding the cans to be washed into said machine, the object of the invention being to provide a simple and effective arrangement of this character by means of which the cans to be washed may be fed into the machine with great efficiency and rapidity.

Other objects will appear hereinafter.

The invention consists in the combinations and arrangements of parts hereinafter described and claimed.

The invention will be best understood by reference to the accompanying drawings forming a part of this specification, and in which,

Fig. 1, is a longitudinal vertical section taken through the feed-in end of a can washing machine embodying the invention,

Fig. 2, a top plan view corresponding with Fig. 1,

Fig. 3, a vertical transverse section of the portion of the machine shown in Figs. 1 and 2, and

Fig. 4, a rear end view of the same.

The preferred form of construction, as illustrated in the drawings, comprises a suitable tank 5 open at the top, and adapted and arranged to contain a considerable body of can-soaking or washing water. Arranged in the tank 5 is an endless chain conveyer 6 having can supporting and feeding fingers 7, 8 and 9 mounted thereon, said conveyer and fingers being so mounted as to cause said fingers to move downwardly adjacent one end of tank 5, as shown. An inclined can supporting chute 10 is arranged at the top of said end of tank 5 in position to deliver cans, such as ordinary ice-cream cans 11, thereto. An oscillatory shaft 12 is mounted transversely under the chute 10 adjacent the corresponding end of tank 5, and said shaft is provided with two stop blades 13 and 14 arranged to project upwardly into the lower end of the chute 10, as indicated. The shaft 12 carries a rocker

arm 15 connected by a link 16 with one arm 17 of a bell crank lever mounted on the tank 5, as indicated. The other arm 18 of said bell crank lever is set in the path of the projecting ends 19 of crossbars 20 on the conveyer 6 and carrying the fingers 7, 8 and 9, the arrangement being such that as the crossbars 20 pass upwardly the bell crank lever 17-18 will be rocked and then released to cause corresponding rocking of the shaft 12. The parts are so balanced and arranged that when thus rocked, they will maintain such position when the arm 18 is thus released. A stop 21 is provided on link 16, and also set in the path of the projecting ends 19 of the crossbars 20, the arrangement being such that immediately following the rocking of the shaft 12 above described, the stop 21 is engaged by the corresponding bar end 19 and the parts restored to original position, as will be readily understood.

In use, the cans are arranged on the chute 10, as indicated in dotted lines. As each set of supporting fingers 7, 8 and 9 pass downwardly into the tank 5, the shaft 12 is oscillated to depress the stop blade 13 and elevate the stop blade 14. This operation releases the lowermost can 11 and permits the same to roll into the tank 5, resting on top of the corresponding downwardly feeding fingers. At the same time, the stop blade 14 is elevated to engage the next can 11 and prevent feeding of it also. When the parts are re-set, as above indicated, said next can will be permitted to roll down into engagement with stop 13 when the operation is repeated. In this manner, it will be observed that as each set of supporting fingers passes downwardly into the tank 5, a can will be automatically deposited thereon. The cans thus deposited are carried downwardly into said tank, where they are washed and treated, as more fully set forth in my co-pending application Serial No. 383,333 filed of even date herewith, and of which the present application is, in effect, a division.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and

modifications as come within the scope of the appended claims.

Having described my invention, what I claim as new and desire to secure by Letters Patent is:—

1. Apparatus of the class described comprising a conveyor; an inclined support leading to said conveyor; an oscillating shaft mounted under said support adjacent said conveyor; two stops mounted on said shaft at an angle to each other and operating within said support; and an operative connection between said conveyor and said shaft for oscillating the same, substantially as described.

2. Apparatus of the class described comprising a conveyor; an inclined support leading to said conveyor; an oscillating shaft mounted under said support adjacent said conveyor; two stops mounted on said shaft at an angle to each other and operating within said support; a bell crank lever set in the path of said conveyor; and an operative connection between said bell crank lever and said shaft for oscillating the shaft, substantially as described.

3. Apparatus of the class described comprising a conveyor; an inclined support leading to said conveyor; an oscillating shaft mounted under said support; two stops on said shaft at an angle to each other and operating in said support; a

rocker arm on said shaft; a bell crank lever having one arm set in the path of said conveyor; a link connecting the other arm of said bell crank with said rocker arm; and a stop on said link set in the path of said conveyor, substantially as described.

4. Apparatus of the class described comprising a tank; an endless conveyer operating vertically in said tank; can supports on said conveyer, said conveyer supports being arranged to cause said supports to feed downwardly adjacent one end of said tank; an inclined can support at the top of said end of said tank; an oscillatory shaft located under said support adjacent said tank end; two can stops arranged on said shaft at an angle to each other and operating in said support; a rocker arm on said shaft; a bell crank lever mounted in operative relation with said conveyer to be oscillated thereby; a link connecting said bell crank lever with said rocker arm; a stop on said link; and means on said conveyer engaging said stop to re-set said shaft, substantially as described.

In testimony whereof I have signed my name to this specification in the presence of two subscribing witnesses.

WALTER H. PAULSON.
